CLAIM

The ornamental design for a bicycle, as shown and described.

DESCRIPTION

FIG. 1 is a front and top perspective view of a bicycle, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown, in a using position;

FIG. 10 is an enlarged perspective view of detail "10" identified in FIG. 1;

FIG. 11 is an enlarged perspective view of detail "11" identified in FIG. 1;

FIG. 12 is an enlarged perspective view of detail "12" identified in FIG. 2;

FIG. 13 is an enlarged perspective view of detail "13" identified in FIG. 2;

FIG. 14 is an enlarged perspective view of detail "14" identified in FIG. 2;

FIG. 15 is an enlarged perspective view of detail "15" identified in FIG. 3; and,

FIG. 16 is an enlarged perspective view of detail "16" identified in FIG. 5.

The dashed lines in the figures illustrate portions of the bicycle that form no part of the claimed design. The broken lines showing of a helmet in FIG. 9 depict environmental structure that form no part of the claimed design. The dash dot dash lines in FIGS. 1, 2, 3, 5, 10, 11, 12, 13, 14, 15 and 16 are for the purpose of illustrating the enlarged views indicators and form no part of the claimed design.

1 Claim, 16 Drawing Sheets
